Sam De John, 4604 SW. 31st Drive, Hollywood, Fla.
33023, and Sheldon Pickover, 91 NW. 162nd St.,
Miami, Fla. 33169

Filed Dec. 3, 1973, Ser. No. 421,441

Term of patent 14 years

Int. Cl. D26—05

U.S. Cl. D48—7 D

FIG. 1

FIG. 2

FIG. 3

FIG. 1 is a bottom plan view of a ceiling ornament for a hanging lamp showing our new design;

FIG. 2 is a side elevational view;

FIG. 3 is a cross-sectional view taken along line 3—3 of FIG. 1; and

FIG. 4 is a top plan view.

We claim:

The ornamental design for a ceiling ornament for a hanging lamp, as shown.
